BATH GLOVE

Anna E. Collins and Linza A. Collins, Stockton, Mo., assignors of twenty-five per cent to Thelma F. Ahl and twenty-five per cent to Harry C. Ahl, Colorado Springs, Colo.

Application April 13, 1954, Serial No. 29,989

Term of patent 14 years

(Cl. D9—2)

Fig. 1.

Fig. 2.

To all whom it may concern:

Be it known that we, Anna E. Collins and Linza A. Collins, citizens of the United States, residing at Stockton, State of Missouri, have invented a new, original, and ornamental Design for a Bath Glove, of which the following is a specification, reference being had to the accompanying drawing, forming a part hereof.

Fig. 1 is a top plan view of a bath glove embodying the invention; and

Fig. 2 is a side or edge elevation thereof.

We claim:

The ornamental design for a bath glove, as shown.
